US00D948032S

(12) **United States Design Patent** (10) **Patent No.:** **US D948,032 S**
(45) **Date of Patent:** **** Apr. 5, 2022**

(54) **ORAL IRRIGATOR**

(71) Applicant: **SHENZHEN FORTUNECOME TECHNOLOGY CO., LTD.**, Shenzhen (CN)

(72) Inventor: **Xiaolin Fang**, Shenzhen (CN)

(73) Assignee: **SHENZHEN FORTUNECOME TECHNOLOGY CO., LTD.**, Shenzhen (CN)

(**) Term: **15 Years**

(21) Appl. No.: **29/738,182**

(22) Filed: **Jun. 15, 2020**

(51) **LOC (13) Cl.** **28-03**

(52) **U.S. Cl.**

USPC **D24/111**

(58) **Field of Classification Search**

USPC D24/108, 111-115, 117, 152, 176;

(57) **CLAIM**

The ornamental design for an oral irrigator, as shown and described.

DESCRIPTION

FIG. 1 is a perspective view of an oral irrigator showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the oral irrigator that form no part of the claimed design.

1 Claim, 8 Drawing Sheets
